UNITED STATES PATENT OFFICE.

WILLIAM WURDACK, OF ST. LOUIS, MISSOURI.

DOOR-OPERATED SWITCH FOR PANEL-BOARDS AND THE LIKE.

1,364,674.

Specification of Letters Patent.

Patented Jan. 4, 1921.

Continuation of application Serial No. 114,404, filed August 11, 1916. This application filed May 14, 1918.
Serial No. 234,450.

To all whom it may concern:

Be it known that I, WILLIAM WURDACK, a citizen of the United States, residing at the city of St. Louis, State of Missouri, have invented certain new and useful Improvements in Door-Operated Switches for Panel-Boards and the like, of which the following is a specification, reference being had to the accompanying drawings, forming a part 10 thereof.

This invention relates generally to metering panel-boards and cabinets and, more particularly, to certain new and useful improvements in door-operated switches for 15 panel-boards and the like.

The objects of my present invention are to provide an efficient metering-panel switch adapted normally, on an opening of the door of the metering-panel cabinet, to automatically open the main circuit to the meter within the cabinet; to provide a cabinet and switch of the class described with means for abnormally, on an opening of the door of the metering-panel cabinet, holding the switch in 25 circuit-closing position; and to improve generally upon, and simplify the construction of, switches of the type stated.

With the above and other objects in view, my present invention resides in certain novel 30 features of form, construction, arrangement, and combination of parts, all as will herein-after be described and afterward pointed out in the claims.

This application is a continuation of Letters Patent No. 1,269,770, issued to me June 35 18, 1918, as to common subject-matter.

In the accompanying drawings—

Figure 1 is a front elevational view of a panel-board cabinet inclosing a panel-board 40 equipped with a switch constructed in accordance with and embodying my invention;

Fig. 2 is a side elevational view of the cabinet with parts broken away and in section to show the panel-board and circuit-45 members, including the switch, within the cabinet, the door of the cabinet being closed and the switch being in circuit-closing position;

Fig. 3 is a transverse sectional view through 50 the cabinet and panel-board on approximately the line 3—3, Fig. 1, the door of the cabinet being closed and the switch being in circuit-closing position;

Fig. 4 is an enlarged fragmental view of 55 the cabinet and panel-board with the switch

abnormally held in circuit-closing position; and

Fig. 5 is an enlarged fragmental vertical sectional view through the cabinet with its door open and the switch in circuit-opening 60 position.

Referring more in detail to the said drawings, in which like reference characters refer to like parts throughout the several views, the cabinet comprises a rear wall 1, end walls 65

2—2, side walls 3—3, and a preferably sectional front wall 4. Suitably disposed and secured within the cabinet, is a panel-board 5. Mounted upon the panel-board 5 are the various circuit-members and parts within 70

the cabinet, including suitable knife-switch or snap-terminals 6, 7, and 8, which are electrically connected, through main fuse plugs 9, 10, and 11, with the main or service lines 12, 13, and 14 of the three-wire system of dis- 75

tribution here shown, leading into the cabinet. Pivoted electrically upon the panel-board 5 adjacent the terminals 6, 7, and 8, is a knife-switch hereinafter more fully de- 80

scribed and which includes an insulation bar 15 having fixed thereto suitable blades 16, 17, and 18 adapted, when the switch is in circuit-closing position, to engage electrically 85

with the several terminals 6, 7, and 8, the blades 16 and 18 communicating electrically 90

through the meter 19 with the several lamp or other distributing circuits and the blade 17 being electrically connected with the return neutral wire or bus-bar of such circuits, all as in my said Letters Patent No. 1,269,770 95

more fully described. It will be evident that, when the switch is in open position or in the position thereof illustrated in Fig. 5, the circuit to the meter 19 from the main leads, and consequently also from the meter 19 to the several lamp or other distributing 100

circuits included in the system, is also open or broken, and that when the switch is in closed position or in the position thereof illustrated in Figs. 2, 3, and 4, the circuit to the meter 19 is likewise closed.

Upstanding from the panel-board 5 adjacent the said switch, is a rigid wall comprising spaced portions 20—20. Fixed to the wall-sections or portions 20, and bridging or spanning the space therebetween, is a rigid 105

section 21 preferably of suitable insulation material, slotted transversely to accommodate a link 22 pivotally connected at one end to the bight of a yoke member 23 having its 110

legs bolted or otherwise rigidly fixed to the knife-bar 15. Link 22 is pivotally connected at its other end to one end of a second link 24, which, in turn, at its free end is pivotally connected to a short rigid bar 25 having its ends bent laterally and bolted or otherwise fixed, as at 26, to said wall-sections 20, the bolts 26 serving also, as seen particularly in Fig. 4, to secure the insulation section 21 in position. Coiled on the bar 25, as seen especially in Fig. 4, are springs 27-27, which bear at one end upon the wall-sections 20 and engage at their other end with link 24, the knife-bar 15 and its several blades 16, 17, and 18 being normally held yieldingly, under the tension of the springs 27, in open or circuit-breaking position or in the said position thereof illustrated in Fig. 5.

To provide convenient means of access for inspection or other purpose to the lamp or other distributing circuit fuses and their associate parts mounted on the panel-board 5 within the cabinet, the front wall 4 of the cabinet is provided with a suitable aperture, as at 28; and hingedly fastened, as at 29, upon the front wall 4 of the cabinet to close the aperture 28, is a swingable door 30 provided with a suitable handle 31 having fixed thereto a suitable latch or catch 32, adapted to project within the cabinet and, on proper turning or manipulation of handle 31, engage with the wall 4 at the lower rim of its aperture 28 to releasably lock the door 30 in aperture-closing position.

Fixed upon the inner face of the door 30, is a suitable rigid curved finger or the like 33 preferably bifurcated or forked at its inner or free end, the finger 33 being adapted, on the closing of the door 30, to engage with switch-link 24 to actuate the switch-bar 15 and its blades 16, 17, and 18, against the tension of springs 27, to circuit-closing position, said blades, under the engagement of the finger 33 with the switch-link 24 while the door 30 is in aperture-closing position, being maintained in engagement with their co-operating terminals 6, 7, and 8 and consequently closing the circuit to and from the meter 19. On the opening of the door 30, it will be evident that, under the tension or pull of the springs 27, the switch with its blades 16, 17, and 18 will automatically move out of electrical engagement with the said terminals 6, 7, and 8 and consequently open or break the circuit to and from the meter 19, at which time all the lamp or other distributing circuit sockets, fuse-plugs, and associate parts within the cabinet may be inspected, repaired, or otherwise handled with safety.

However, it may be desirable at times to inspect the lamp or other distributing circuits and their associate parts within the cabinet without cutting off or breaking the circuit to and from the meter, and for such

purpose I provide means for abnormally, as I have called it, holding the switch in circuit-closing position when the door 30 is open. Such means preferably includes a pivot-pin or the like 34 loosely disposed transversely through the cabinet-wall 4 and provided exteriorly of the cabinet with a convenient manipulating knurled head or the like 35. Having a laterally disposed lipped portion 36 bolted or otherwise rigidly fixed to, and upon the inner end of, pin 34, is a switch-engaging member 37 provided transversely at its end with a shallow groove, as at 38, to accommodate the switch-link 22 when the member 37 is in switch engaging position, the member 37 being also provided with an extension 39 adapted to engage the switch-link 22 to limit the movement of member 37 to switch engaging position. Having one end secured to a screw or the like 40 seated in cabinet front wall 4 and its other end suitably attached to the member 37, is an extensible coil spring 41 adapted to yieldingly hold the member 37 in normal, non-switch-engaging position. Normally, either when the door 30 and consequently also the switch are open or in the position thereof illustrated in Fig. 5, or when the door 30 and consequently also the switch are in fully closed position, or in the position thereof illustrated in full lines in Fig. 2, the member 37 has no function to perform. When, however, it is desired to open the door 30 without at the same time cutting off or breaking the circuit to and from the meter 19, and while the door 30 is yet in closed position, the head 35 is suitably manipulated to swing the member 37 against the tension of its spring 41 into switch-engaging position or into the position thereof illustrated in Figs. 3 and 4. With head 35 and member 37 suitably held, as by the fingers manually or otherwise, in such position, the door 30 is opened, when the switch-link 22, rising somewhat from full circuit-closing position, will engage with the then interfering member 37 and its groove 38. With the switch-link 22 so held under the tension of the switch-springs 27 in engagement with the member 37 and with the door 30 now open, so that access into the cabinet may be conveniently had, the switch-blades 16, 17, and 18 continue in electrical engagement with the terminals 6, 7, and 8 and accordingly continue to close the circuit to and from the meter 19. When door 30 is again closed and the switch again actuated to fully closed position, as before described, link 22 will be moved out of engagement with the member 37, member 37 with its manipulating head or knob 35 returning, under the pull or tension of the spring 41, to normal, non-switch-engaging position.

I am aware that changes in the form, construction, arrangement and combination of

the several parts of the switch and its operating and locking members may be made and substituted for those herein shown and described without departing from the nature 5 and principle of my invention.

Having thus described my invention, what I claim and desire to secure by Letters Patent is:

1. An electric switch comprising, in combination with a panel, a fixed support on the panel, a switch-bar pivoted for movement upon the panel, a link having pivotal connection at one end with the bar, a second link having pivotal connection at one end 10 with the support and at its other end with the other end of the first link, and a spring coiled on the support and having engagement with the support and the second link for holding the bar yieldingly in circuit- 15 opening position.

2. An electric switch comprising, in combination with a fixed slotted support and a rod fixed on the support, a bar, a link having pivotal connection at one end with the bar 20 and working in the slot of the support, a second link having pivotal connection at one end with the rod and at its other end with the other end of the first link, and a spring coiled on the rod and having engagement 25 with the support and the second link for holding the bar yieldingly in circuit-opening position.

3. The combination with an inclosing cabinet, of an electric circuit knife-switch pivotally mounted within the cabinet, means including a spring engaging the switch for normally holding the same yieldingly in circuit-opening position, and means including a member mounted for movement on 30 the cabinet and relatively to the switch adapted for engagement with the switch when the same is in circuit-closing position to hold the switch against the tension of the spring in circuit-closing position.

4. The combination with an inclosing cabinet, of an electric circuit knife-switch pivotally mounted within the cabinet, means including a spring engaging the switch for normally holding the same in circuit-opening 45 position, and means including a yieldingly held member mounted for pivotal movement on the cabinet and swingable relatively to the switch adapted for engagement with the switch when the same is in 50 circuit-closing position to hold the switch against the tension of the spring in circuit-closing position.

5. The combination with an inclosing

cabinet and a fixed switch support mounted within the cabinet, of an electric circuit 60 knife-switch bar disposed for movement within the cabinet, a link having pivotal connection at one end with the bar, a second link having pivotal connection at one end with the support and at its other end 65 with the other end of the first link, a spring having engagement with the support and one of the links for holding the bar yieldingly in circuit-opening position, and means including a yieldingly held member mounted 70 for pivotal movement on the cabinet and swingable relatively to the bar adapted for engagement with one of the links when the bar is in circuit-closing position to hold the same in such position against the tension of 75 the spring.

6. The combination with an inclosing cabinet having an aperture and a door upon the cabinet for closing said aperture, of an electric circuit knife-switch pivotally 80 mounted within the cabinet, means including a spring engaging the switch for normally holding the switch yieldingly in circuit-opening position, means on the door adapted for engagement with the switch to 85 hold the same against the tension of said spring in circuit-closing position when the door is closed, and means on the cabinet adapted for engagement with the switch to hold the same against the tension of said 90 spring in circuit-closing position when the door is open.

7. The combination with an inclosing cabinet having an aperture, a door mounted for movement upon the cabinet for closing 95 said aperture, and a fixed switch-support within the cabinet, of an electric circuit knife switch bar disposed for movement within the cabinet, a link having pivotal connection with the bar, a second link having pivotal connection with the support and with the first link, a spring having engagement with one of the links for normally holding the bar yieldingly in circuit-opening 100 position, means on the door adapted for engagement with one of said links to hold the bar against the tension of the spring in circuit-closing position when the door is closed, and means on the cabinet adapted for engagement with the other of said links 105 to hold the bar against the tension of the spring in circuit-closing position when the door is open.

In testimony whereof, I have signed my name to this specification.

WILLIAM WURDACK.
